UNITED STATES PATENT OFFICE.

JOSEPH B. EDWARDS, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

DESIGN FOR A CONTROL DIAL.

Application filed October 9, 1922. Serial No. 3,912. Term of patent 14 years.

To all whom it may concern:

Be it known that I, JOSEPH B. EDWARDS, a citizen of the United States of America, residing at Chicago, in the county of Cook and State of Illinois, have invented a new, original, and ornamental Design for Control Dial, of which the following is a specification, reference being had to the accompanying drawing, forming part thereof.

The figure is a perspective view of a control dial showing my new design.

I claim:

The ornamental design for a control dial as shown.

JOSEPH B. EDWARDS.
